UNITED STATES PATENT OFFICE.

NEIL W. MACINTOSH, OF NEW YORK, N. Y.

FIRE-ARCH FOR STEAM-BOILERS.

SPECIFICATION forming part of Letters Patent No. 712,695, dated November 4, 1902.

Application filed November 7, 1901. Serial No. 81,368. (No model.)

To all whom it may concern:

Be it known that I, NEIL W. MACINTOSH, a citizen of the United States, residing at the borough of the Bronx, city of New York, in 5 the county of New York and State of New York, have invented certain new and useful Improvements in Fire-Arches for Steam-Boilers, of which the following is a specification, reference being had therein to the accompanying drawings.

My invention relates to steam-boilers and boiler-furnaces, and particularly to a water-arch located at the front of a boiler. This water-arch is designed to take the place of the 15 brick arch usually built over the furnace-door just in front of the boiler, and it is also designed to act as a feed-water heater and settling-chamber, and in accordance with my invention means are provided for at all times 20 maintaining this water-arch full of water and for feeding water into the boiler and discharging water out of the boiler through this water-arch and for removing from this water-arch the sediment which will collect therein.

25 I will describe a steam-boiler having my invention applied thereto and then point out the novel features thereof in the claims.

In the accompanying drawings, Figure 1 is 30 a view, partly in elevation and partly in vertical section, of a steam-boiler furnace and appurtenant parts having my invention applied thereto. The section is taken on a plane in front of the boiler. Fig. 2 is a central vertical and longitudinal sectional view of the 35 parts shown in Fig. 1, the boiler being shown in elevation.

The boiler 1 here shown is of the well-known tubular type and is supported in the usual manner. Beneath the boiler, at its front end, 40 is the usual combustion-chamber 2, a grate 3, the connecting-bridge 4 at the rear of the combustion-chamber, and the ash-pit 5 beneath the grate 3. The front wall 6 of the furnace is provided with the usual door or doors 7 for 45 the ash-pit.

Mounted upon the usual dead-plate 8, which forms the lower wall of the fuel-opening in front of the combustion-chamber and beneath the boiler, is a chamber or receptacle 9, which 50 constitutes a water arch or bridge and feed-water heater. The ends of the arch are embedded in the side walls of the furnace. The

chamber or arch 9 is preferably of steel, and, as here shown, its lower wall is arched or curved and constitutes the upper and side 55 walls of the fuel-opening. The upper or top wall of the chamber is shown as being straight, though, if desired, it may be circular and conform to the outer surface of the boiler. Brick or other equivalent material 10 may be used 60 to close the space between the top of the chamber and the boiler. The front wall of the chamber or receptacle 9 is flush with the front wall 6 of the furnace. The usual door 11 for the fuel-passage may be supported on the 65 front wall of the chamber 9.

The arch or chamber 9 is adapted to contain water at all times, and the water supplied to the boiler first passes through it. In this manner the arch or chamber constitutes 70 a settling-chamber. A blow-off pipe 12, having the usual valve, (not shown,) is provided for the chamber, and the boiler is blown off through the chamber and pipe. The water is supplied to the arch through a supply-pipe 75 13. The water passes into the boiler through a pipe 14. The pipe 14 enters the boiler at a low level, considerably below the water-line thereof, and leaves the arch at a high level. With this arrangement of water-feed the wa- 80 ter is heated to a considerable extent before entering the boiler, and it is introduced into the boiler at the lower portion thereof, where it is subjected to the greatest heat. A more rapid heating of the water will therefore re- 85 sult. Any steam that may be generated in the arch, chamber, or bridge 9 has a free passage therefrom to the steam-space of the boiler through a pipe or conduit 15, which extends from the upper part of the water-arch to the 90 steam-space of the boiler, and which also serves to maintain an equilibrium of pressure in the water-arch and boiler. Thus I prevent any possibility of forcing the water out of the water-arch by the generation of steam within 95 the water-arch and assure that the water-arch shall be at all times full of water.

The constant presence of water in the wa- 100 ter-arch protects the metal parts from extreme heat and variations of temperature, and there is no bulging of the front wall of the furnace, such as usually results in a brick-filled arch from the extreme and variable temperatures present at this part of a boiler-furnace.

As aforesaid, the water-chamber 9 acts as a settling-chamber, receiving practically all the sediment and deposits from the water, and I provide removable means for access to the water-chamber for cleaning out such sediment and deposits therefrom, such means being shown as consisting of hand-pole plates 16 of usual construction.

It is evident that modifications may be made 10 in the construction shown and above particularly described within the spirit and scope of my invention.

Having now described my invention, what I claim, and desire to secure by Letters Patent, is—

1. The combination of a steam-boiler and furnace, a combustion-chamber, the wall of the furnace having a fuel-opening, a water-chamber located at the front of the combustion-chamber and about the fuel-opening, a water-supply conduit entering the water-chamber, a conduit extending from the upper part of the water-chamber and entering the boiler at a low level, and another conduit 25 extending from the upper part of the water-

chamber and entering the boiler in the steam-space thereof.

2. The combination of a steam-boiler and furnace, a combustion-chamber, the wall of the furnace having a fuel-opening, a water-chamber located at the front of the combustion-chamber and about the fuel-opening and below the level of the lowest part of the boiler, a water-supply conduit entering the water-chamber, a conduit extending from the upper part of the water-chamber and entering the boiler at a low level, another conduit extending from the upper part of the water-chamber and entering the boiler at a high level, a blow-off pipe for the boiler extending 35 from the lower part of the water-chamber, and removable means located at lower parts of the water-chamber for access to the interior thereof, substantially as set forth.

In testimony whereof I have affixed my signature in presence of two witnesses.

NEIL W. MACINTOSH.

Witnesses:

HENRY D. WILLIAMS,
ARCHIBALD MCINTOSH.
